UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed February 7, 1929. Serial No. 338,287.

This invention relates to mining machines and more particularly, but not exclusively, to coal mining machines of the flexibly fed, continuous cutter type.

An object of this invention is to provide an improved mining machine. Another object is to provide an improved coal mining machine of the flexibly fed, continuous cutter type having improved means for feeding and controlling movement of the machine during the cutting operation and for moving the machine about the mine. A further object is to provide an improved coal mining machine of the flexibly fed, continuous cutter, room and pillar type having improved flexible feeding means whereby the machine may be fed in a more flexible and advantageous manner. Still another object is to provide an improved coal mining machine of the flexibly fed, continuous cutter, room and pillar type having improved flexible feeding means of the multiple haulage drum type and improved plural speed reversible driving connections for the haulage drums. These and other objects and advantages of this invention will, however, hereinafter more fully appear.

In the accompanying drawings there is shown for purposes of illustration one form 30 which the invention may assume in practice.

In these drawings,—

Fig. 1 is a top plan view, partially broken away in horizontal section to illustrate details of construction, of the improved mining machine.

Fig. 2 is an enlarged central longitudinal vertical sectional view taken substantially on line 2—2 of Fig. 1.

Fig. 3 is a transverse vertical sectional view taken substantially on line 3—3 of Fig. 2.

Fig. 4 is a detail sectional view taken on line 4—4 of Fig. 3.

In this illustrative form of the invention there is shown a coal mining machine of the flexibly fed, continuous cutter type and generally comprising a machine frame 1 having a plane bottom surface 2 on which the machine is slidably supported for movement over the mine floor. Projecting forwardly 45 lengthwise of the machine frame and rigidly

connected thereto is an elongated horizontal plane cutter bar 3 having thereon for circulation orbitally about its margin an endless cutter bit carrying cutter chain 4. Mounted on the opposite sides of the rearward end of the machine frame on transversely extending horizontal axes are coaxially arranged relatively rotatable feeding and controlling members herein in the form of haulage drums 5 and 6 with which flexible feeding means in 55 the form of haulage cables 7 and 8 respectively cooperate. Mounted on the opposite sides of the forward end of the machine frame are guide sheaves 9 while mounted on the opposite rear corners of the machine frame are 60 similar guide sheaves 10, these guide sheaves being adapted to guide the haulage cables 7 and 8 during the various operations of the machine. Arranged within the forward end of the machine frame is a motor 11 adapted 65 to effect drive, through improved transmission mechanism to be later described, of the haulage drums and cutter chain.

The mechanism for actuating the cutter chain 4 will now be described. It will be 75 noted that the motor 11 is herein preferably of the usual electric reversible type having its armature shaft 12 horizontally disposed and extending longitudinally of the machine. Fixed to the rear end of the armature shaft 80 12 and rotatable therewith is a bevel pinion 13 meshing with a horizontal bevel gear 14 suitably fixed to a vertical shaft 15 suitably journaled within the frame of the machine. As shown in Fig. 2, formed integral with the 85 vertical shaft 15 is a spur pinion 16 meshing with a large spur gear 17 having its hub portion journaled on the upstanding sleeve portion of a member 18. The member 18 is keyed to a vertical shaft 19 journaled 90 within bearing sleeves 20 and 21 suitably carried within the machine frame. As is usual in machines of the type disclosed, the spur gear 17 is connectible, by a clutch mechanism 22 of the usual pin type, to a cutter chain driving sprocket 23. The clutch mechanism 22 has operating means of any suitable form and as the detailed construction of this clutch and the controlling means therefor does not enter into this invention 95 100

further description of the same is herein thought to be unnecessary. As illustrated, the cutter chain drive sprocket 23 is journaled on a bearing sleeve 24 supported by 5 the member 18 and an underlying flanged member 25, the members 17 and 25 being secured to the hub of the gear 17 by bolts 26. Interposed between the members 25 and 17 and engaging the lower portion of the machine frame is a ball thrust bearing 27. The 10 cutter chain drive sprocket 23 engages and drives the cutter chain 4 in a usual manner, the cutter chain drive sprocket being connectible to and disconnectible from the motor 16 at will. It will also be noted that meshing with the spur gear 17 is a spur truck driving gear 28 journaled on a vertical stud 29 supported on an overlying flange portion 30 of the machine frame. The truck driving gear 28 is adapted to engage the usual driving element on the transport truck for the machine to effect propulsion of the truck about the mine by power from the driving motor 11 of the machine thereon.

23 Journalled on a bearing sleeve 35 supported by the upper end of the vertical shaft 19 is a spur pinion 36 adapted to be driven by shaft 19 through a reversible friction device generally designated 37 hereinafter described in detail. Rotatable on parallel vertical axes disposed in the same transverse vertical plane at opposite sides of the machine and meshing with the opposite sides of the spur pinion 36 are spur gears 38 and 39. The gears 38, 39 are respectively secured at 40 and 41 to the lower ends of vertical shafts 42 and 43. The shafts 42, 43 are each journaled at their ends in ball bearings 44 suitably carried by the machine frame. Referring to the fast speed driving connections for the haulage drums it will be observed that secured to the vertical shaft 42 is a fast speed worm 45 meshing with a worm wheel 46 journaled on ball bearings 47 supported on a transversely extending horizontal main drive shaft 48 herein arranged parallel with the drum axes. The transverse drive shaft 48 is journaled at its opposite ends in ball bearings 49 suitably supported on the side walls of the machine frame. Carried by a laterally projecting sleeve portion 50 on the worm wheel 46 is a series of clutch discs 51 interleaved with a corresponding series of clutch discs 52 carried by a clutch member 53 keyed to the shaft 48. Keyed at 54 to the opposite ends of the shaft 48 are slidable clutch pinions 55 and 56 respectively adapted to mesh with spur gears 57 and 58. The gears 57 and 58 are respectively keyed at 59 to horizontal transversely extending shafts 60 arranged parallel with the shaft 48 and journaled in ball bearings 61 slidably supported within the frame of the machine. Secured to the 65 outer ends of each of the shafts 60 is a spur

pinion 62, these pinions meshing respectively with internal gears 63 and 64 formed on the haulage drums 5 and 6 respectively. As shown in Fig. 1 the haulage drums 5 and 6 are each journaled on laterally projecting studs 65 mounted on the sides of the machine frame and held in position on the studs by suitable screw and washer connections 66. It will thus be seen that when the fast speed controlling clutch 51, 52 is applied the haulage drums 5 and 6 are adapted to be driven at a relatively fast speed and in opposite directions at such speed under the control of the reversible friction device 37.

The slow speed transmission for effecting drive of the haulage drums 5 and 6 at a slow speed herein comprises a slow speed worm 67 secured to the vertical shaft 48 and meshing with a worm wheel 68 journaled on ball bearings 69 supported by the transverse shaft 48. The worm wheel 68 has a laterally projecting sleeve-like portion 70 which carries a series of clutch discs 71 which are interleaved with a corresponding series of clutch discs 72 carried by a clutch member 73 keyed to the shaft 48. The teeth on the worm 45 are of steeper inclination than the teeth on the worm 67 and these worms rotate in the same direction to effect drive of the worm wheels in the same direction. It will thus be seen that when the clutch 71, 72 is applied the haulage drums 5 and 6 are adapted to be driven at a relatively slow speed and in opposite directions at such speed under the control of the reversible friction device 37. It will also be evident that the spur pinions 55, 56 may be slid inwardly from the position shown in Fig. 1 thereby disconnecting the drive of the transmission shaft 48 from the haulage drums, thereby permitting free rotation of the latter. The mechanisms for shifting the spur pinions 55, 56 each comprises a pivoted shipper yoke 74 secured to an operating shaft 75, these shafts carrying respectively at their outer ends operating levers 76, 77. The operating mechanism for the fast and slow speed friction clutches comprises slidable clutch applying members 78, 79 surrounding and mounted on the shaft 48 and interposed between these members is a pivoted shipper member 80 secured to an operating shaft 81. The shaft 81 carries at its outer end an operating lever 82.

The improved reversible friction device 37 above referred to herein comprises a sleeve 83 keyed at 84 to the upper end of the vertical shaft 19 (see Figs. 3 and 4). The sleeve 83 carries a series of friction clutch discs 85 which are interleaved with a series of clutch discs 86 carried by a bevel gear 87 herein formed integral with the hub of the spur pinion 36. Meshing with the bevel gear 87 is a plurality of bevel pinions 88, herein three, rotatably mounted on radial studs 89 carried by the clutch housing 90. It will be noted

that the housing 90 is provided with a laterally projecting lug 91 engaging stops 92 on the frame of the machine. The bevel pinions 88 mesh with a bevel gear 93 rotatably mounted 5 on the clutch housing 90 and carrying a series of friction clutch discs 94 interleaved with clutch discs 95 carried by a slideable clutch applying member or sleeve 96. The clutch applying member 96 has a radial flange 97 10 projecting between and engageable with the end discs of the friction clutches. As shown in Fig. 3, the clutch member 96 is slidably mounted on a sleeve or bushing 98 threadedly connected at 99 to the upper end of the vertical shaft 19, the member 96 having arms 100 which slide in longitudinal grooves 101 in the sleeve 83 thereby forming an interlocking connection between the parts. Downward movement of the clutch applying member 96 15 renders operative the clutch 85, 86 to connect the sleeve 83 with the gear 87, while upward movement of said clutch applying member 96 disengages the clutch 85, 86 and renders operative the clutch 94, 95 to connect the sleeve 83 with the bevel gear 93. When the gear 93 is clutched to the sleeve 83 it will be seen that the pinion 36 will be rotated from the vertical shaft 19 through the bevel gear 93, pinions 88, and bevel gear 87 and in a 20 direction opposite from the direction of rotation of said shaft. When the pinion 36 is directly connected to the sleeve 83 by the clutch 85, 86 it will be seen that this pinion will be rotated by the shaft 19 and in the 25 same direction.

For operating the clutch applying member 96 there is provided a sleeve 102 slidably mounted on the exterior of the upper sleeve portion 103 of the clutch applying member 40 96, said sleeves 102 and 103 having respectively internal and external shoulders 104 and 105. The outer end of the sleeve 102 is interiorly threaded to receive a bushing 106 and a nut 107 is threaded on the exteriorly threaded outer end of the sleeve 103. Engaging the bushing 106 and the nut 107 is a washer 108, while engaging the shoulders 104, 105 is a similar washer 109 and between said washers 108, 109 is interposed a coil spring 110. As 45 50 55 60 65 70 75 80 85 90 95 100 105 110 115 120 125 130 will now be seen downward movement of the sleeve 102 will cause, through the bushing 106 and washer 108, a compression of spring 110, which will be communicated through the washer 109 and shoulder 104 to the clutch applying member 96, causing downward movement of said member and thereby rendering operative the clutch 85, 86 to connect the sleeve 83 to the spur pinion 36. Similarly, upward movement of the sleeve 102 acting 60 65 70 75 80 85 90 95 100 105 110 115 120 125 130 through the shoulder 104 and washer 109, will compress the spring 110, the tension of which will be transmitted through the washer 108 and the nut 107 to the clutch applying member 96, causing upward movement of said member thereby rendering operative the

clutch 94, 95 to connect the sleeve 83 and bevel gear 93. It will be seen that movement of the sleeve 102 in either direction is yieldingly transmitted to the clutch applying member 96 through the spring 110. For moving the sleeve 102, there is provided a trunnion ring 111 interposed between an annular flange 112 on the sleeve 102 and a nut 113 in threaded engagement with the exterior of said sleeve. The ring 111 is provided with trunnions 114 which are engaged by the forked end of a lever 115 pivotally mounted on a transverse shaft 116 suitably supported by the machine frame. The lever 115 has an upstanding lever portion or arm 117 suitably connected at 118 to a reciprocable operating rod 119. The outer end of the rod 119 is threaded at 120 and is engaged by a nut 121 rotatably mounted on the machine frame and having an operating handle 122. By moving the lever 123 115 in one direction or the other it will be seen that, through the connections described, the pinion 36 may be connected with the shaft 19 for rotation in either direction, causing, through the transmission connections described, a rotation of the haulage drums 5 and 6 in either direction. It will thus be seen that upon application of one or the other of the speed controlling clutches and upon suitable application of the reverse frictions 128 133 the haulage drums 5 and 6 may be rotated at a fast or a slow speed in one direction and at a fast or slow speed in the opposite direction without reversing the motor.

The operation of the improved mining machine is as follows. The mining machine is transported about the mine while supported on its transport truck which is driven by the motor 11 of the machine through bevel gearing 13, 14, and spur gearing 16, 17, and 28, the latter gear engaging the usual truck driving element on the truck. It will be evident that upon reversal of the motor 11 the transport truck may be propelled along the mine trackway in an opposite direction. When the working face is reached the mining machine is unloaded from the truck in a well known manner and one or the other of the haulage cables 7, 8 is connected to an anchor or roof jack disposed adjacent the coal face at the right hand rib of the room. The fast speed friction 51, 52 is then applied connecting the worm wheel 46 to the shaft 48 and as a result the haulage cable is wound in by the fast speed worm gearing at a relatively fast speed and the machine is slid over the mine bottom to a position adjacent the right hand corner of the room. The slow speed clutch 70, 71 is then applied and the haulage cable is wound in at a relatively slow speed thereby sumping the cutter bar beneath the coal face. The advance haulage cable 7 is then connected at its free end to an anchor or roof jack adjacent the coal face at the left hand rib while the receding haulage cable 8 is at 130

its free end connected to a roof jack adjacent the right hand rib. Under suitable control of the several controlling clutches the machine is straightened up and fed transversely across the face at a cutting speed, the haulage drum 5 winding in the haulage cable 7 at a slow cutting speed while the haulage drum 6 pays out the receding haulage cable 8. If it is desired to angle the machine during the transverse cutting operation it is obvious that the haulage cable 8 may be wound in by the drum 6 at a fast speed to swing the rear end of the machine rearwardly and upon suitable control of the haulage drums 5 and 6 the machine may be angled in either direction as desired. When the transverse cut is completed the machine is angled in the usual manner and the free end of the haulage cable 7 is connected to a roof jack located in the rear of the machine and the cutter bar withdrawn from the face at a cutting speed. The mining machine is then hauled over the mine bottom at a fast speed and again loaded on the transport truck and moved to another working place. It is also evident that during the cutting operation the haulage drums may be rotated to unwind or wind in their respective haulage cable at a fast or a slow speed and in either direction at each speed under the control of the reversible friction device 37 and that the drums may be disconnected from the drive to permit free rotation of the drums under the control of the slideable clutch pinions 55 and 56. It will further be noted that when the motor 11 is reversed, the cutter bits turned in their respective links, and the haulage cables extended in an opposite direction the machine may be fed across the coal face from left to right. Other operations of the improved mining machine will be clearly apparent to those skilled in the art.

As a result of this invention it will be noted that an improved coal mining machine of the flexibly fed continuous cutter type is provided having improved flexible feeding means of the multiple haulage drum type and improved mechanism for effecting drive of the haulage drums. It will further be noted that an improved reversible plural speed transmission mechanism is provided for the haulage drums to effect drive of the drums in either direction at high or slow speeds thereby increasing the flexibility of operation of the machine. It will still further be noted that an improved coal mining machine of the flexibly fed continuous cutter room and pillar type is provided which is of an exceedingly simple, compact and rugged design especially adapted to meet the severe demands of service encountered in mines.

While there is in this application specifically described one form which the invention may assume in practice it will be understood that this form has been shown for purposes

of illustration and that the invention may be modified and embodied in various other forms without departing from its spirit or the scope of the appended claims.

What I claim as new and desire to secure by Letters Patent is:

1. In a mining machine, a machine frame slideable on its bottom on the mine floor, a motor carried by said frame, kerf cutting mechanism driven by said motor including a cutter bar projecting from said frame, and feeding means for the machine including relatively rotatable feed operating members each adapted to cooperate with flexible feeding means, and driving connections between said motor and feed operating members including means for effecting drive of said feed operating members at fast and slow speeds and in opposite directions at either speed without reversing said motor.

2. In a mining machine, a machine frame slideable on its bottom on the mine floor, a motor carried by said frame, kerf cutting mechanism driven by said motor including a cutter bar projecting from said frame, and feeding means for the machine including relatively rotatable feed operating members disposed at the end of the machine frame remote from the end thereof from which said cutter bar projects and each adapted to cooperate with flexible feeding means, and driving connections between said motor and feed operating members including means for effecting drive of said feed operating members at fast and slow speeds and in opposite directions at either speed without reversing said motor.

3. In a mining machine, a machine frame slideable on its bottom on the mine floor, a motor carried by said frame, kerf cutting mechanism driven by said motor including a cutter bar projecting from said frame, feeding means for the machine including relatively rotatable feed operating members disposed on horizontal axes each adapted to cooperate with flexible feeding means, and driving connections between said motor and feed operating members including means for effecting drive of said feed operating members at fast and slow speeds and in opposite directions at either speed without reversing said motor.

4. In a mining machine, a machine frame slideable on its bottom on the mine floor, a motor carried by said frame, kerf cutting mechanism driven by said motor including a cutter bar projecting from said frame, feeding means for the machine including relatively rotatable feed operating members coaxially arranged and each adapted to cooperate with flexible feeding means, and driving connections between said motor and feed operating members including means for effecting drive of said feed operating members at fast and slow speeds and in

- opposite directions at either speed without reversing said motor.
5. In a mining machine, a machine frame 50
slidable on its bottom on the mine floor, a
motor carried by said frame, kerf cutting
mechanism driven by said motor including a
cutter bar projecting from said frame, and
feeding means for the machine including
relatively rotatable haulage drums and coop- 70
erating haulage cables, and driving connec-
tions between said motor and said drums in-
cluding means for effecting drum drive at
fast and slow speeds and in opposite direc- 75
tions at each speed without reversing said
motor.
10. In a mining machine, a machine frame
slidable on its bottom on the mine floor, a
motor carried by said frame, kerf cutting 80
mechanism driven by said motor including
a cutter bar projecting from said frame, and
feeding means for the machine including rela-
tively rotatable haulage drums disposed on
horizontal axes and cooperating haulage ca- 85
bles, and driving connections between said
motor and said drums including means for
effecting drum drive at fast and slow speeds
and in opposite directions at each speed with- 90
out reversing said motor.
11. In a mining machine, a machine frame
slidable on its bottom on the mine floor, a
motor carried by said frame, kerf cutting 95
mechanism driven by said motor including a
cutter bar projecting from said frame, and
feeding means for the machine including rela-
tively rotatable haulage drums coaxially ar-
ranged and cooperating haulage cables, and 100
driving connections between said motor and
said drums including means for effecting
drum drive at fast and slow speeds and in
opposite directions at each speed without re-
versing said motor.
12. In a mining machine, a machine frame
slidable on its bottom on the mine floor, a 105
motor carried by said frame, kerf cutting
mechanism driven by said motor including a
cutter bar projecting from said frame, and
feeding means for the machine including rela-
tively rotatable haulage drums coaxially ar- 110
ranged and disposed on horizontal transverse
axes and cooperating haulage cables, and
driving connections between said motor and
said drums including means for effecting
drum drive at fast and slow speeds and in op- 115
posite directions at each speed without re-
versing said motor.
13. In a mining machine, a machine frame
slidable on its bottom on the mine floor, a
motor carried by said frame, kerf cutting 120
mechanism driven by said motor including
a cutter bar projecting from said frame, and
feeding means for the machine including rela-
tively rotatable haulage drums and coop-
erating haulage cables, and driving connec- 125
tions between said motor and said drums including
a reversible friction device for effecting drum
drive at fast and slow speeds and in opposite
directions at each speed without reversing
said motor.
14. In a mining machine, a machine frame
slidable on its bottom on the mine floor, a
motor carried by said frame, kerf cutting 130
mechanism driven by said motor including a
cutter bar projecting from said frame, and
feeding means for the machine including rela-
tively rotatable haulage drums and coop-
erating haulage cables, and driving connec-
tions between said motor and said drums including
a reversible friction device for effecting drum
drive at fast and slow speeds and in opposite
directions at each speed without reversing
said motor.

14. In a mining machine, a machine frame 50
slidable on its bottom on the mine floor, a
motor carried by said frame, kerf cutting
mechanism driven by said motor including a
cutter bar projecting from said frame, and
feeding means for the machine including rel-
atively rotatable haulage drums and cooper-
ating haulage cables, and driving connections
between said motor and said drums includ-
ing a frictionally controlled plural speed
transmission mechanism for effecting drum
drive at fast and slow speeds and in opposite
directions at each speed without reversing
said motor.
15. In a mining machine, a machine frame 55
slidable on its bottom on the mine floor, a
motor carried by said frame, kerf cutting
mechanism driven by said motor including a
cutter bar projecting from said frame, and
feeding means for the machine including rel-
atively rotatable haulage drums and cooper-
ating haulage cables, and driving connections
between said motor and said drums includ-
ing a reversible friction device and friction-
ally controlled plural speed transmission
mechanism for effecting drum drive at fast
and slow speeds and in opposite directions
at each speed without reversing said motor.
16. In a mining machine, a machine frame 60
slidable on its bottom on the mine floor, a
motor carried by said frame, kerf cutting
mechanism driven by said motor including
a cutter bar projecting from said frame, and
feeding means for the machine including
relatively rotatable feed operating members
each adapted to cooperate with flexible feed-
ing means, and driving connections between
said motor and said feed operating members
including separate fast and slow speed worm
gear trains for effecting drum drive of said
feed operating members at fast and slow
speeds and in opposite directions at either
speed without reversing said motor.
17. In a mining machine, a machine frame 65
slidable on its bottom on the mine floor, a
motor carried by said frame, kerf cutting
mechanism driven by said motor including
a cutter bar projecting from said frame, and
feeding means for the machine including rel-
atively rotatable feed operating members
each adapted to cooperate with flexible feed-
ing means, and driving connections between
said motor and said feed operating members
including separate frictionally controlled
fast and slow speed worm gear trains for
effecting drum drive of said feed operating
members at fast and slow speeds and in op-
posite directions at either speed without re-
versing said motor.
18. In a mining machine, a machine frame 70
slidable on its bottom on the mine floor, a
motor carried by said frame, kerf cutting
mechanism driven by said motor including
a cutter bar projecting from said frame,
and feeding means for the machine including
relatively rotatable feed operating members
each adapted to cooperate with flexible feed-
ing means, and driving connections between
said motor and said feed operating members
including separate fast and slow speed worm
gear trains and a reversible friction device
for effecting drum drive of said feed operating
members at fast and slow speeds and in op-
posite directions at either speed without re-
versing said motor.
19. In a mining machine, a machine frame 75
slidable on its bottom on the mine floor, a
motor carried by said frame, kerf cutting
mechanism driven by said motor including
a cutter bar projecting from said frame, and
feeding means for the machine including rel-
atively rotatable feed operating members
each adapted to cooperate with flexible feed-
ing means, and driving connections between
said motor and said feed operating members
including separate frictionally controlled
fast and slow speed worm gear trains and
a reversible friction device for effecting drum
drive of said feed operating members at fast
and slow speeds and in opposite directions
at either speed without reversing said motor.
20. In a mining machine, a machine frame 80
slidable on its bottom on the mine floor, a
motor carried by said frame, kerf cutting
mechanism driven by said motor including
a cutter bar projecting from said frame,
and feeding means for the machine including
relatively rotatable haulage drums and co-
operating haulage cables, and driving connec-
tions between said motor and said drums
including separate frictionally controlled
fast and slow speed worm gear trains and
a reversible friction device for effecting drum
drive at fast and slow speeds and in op-
posite directions at each speed without re-
versing said motor.
21. In a mining machine, a machine frame 85
slidable on its bottom on the mine floor, kerf
cutting mechanism carried by said frame in-
cluding an elongated kerf cutter projecting
from said frame, a motor, and feeding means
for the machine driven by said motor includ-
ing relatively rotatable feed operating mem-
bers each adapted to cooperate directly with
flexible feeding means, and mechanism
driven by said motor for driving said mem-
bers at either a relatively fast speed or a
relatively slow speed and including means
for effecting rotation of one of said mem-
bers in opposite directions at either speed
without reversing said motor.
22. In a mining machine, a machine frame 90
slidable on its bottom on the mine floor, kerf
cutting mechanism carried by said frame in-
cluding an elongated kerf cutter projecting
from said frame, a motor, and feeding means
for the machine driven by said motor includ-
ing relatively rotatable feed operating mem-
bers each adapted to cooperate directly with
flexible feeding means, and mechanism

driven by said motor for driving said members at either a relatively fast or a relatively slow speed and including means for effecting rotation of either or both of said members in opposite directions at either speed without reversing said motor.

23. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and mechanism driven by said motor for driving said members in a direction to draw in their respective flexible feeding means at either a relatively slow or a relatively fast speed and including means for effecting rotation of one of said members in opposite directions at either speed without reversing said motor.

24. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and mechanism driven by said motor for driving said members in a direction to draw in their respective flexible feeding means at either a relatively fast or a relatively slow speed and including means for effecting rotation of either or both of said members in opposite directions at either speed without reversing said motor.

25. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and motor driven mechanism for driving said members simultaneously or separately in a direction to draw in their respective flexible feeding means at either a relatively high speed or a relatively low speed and including means for effecting rotation of said members in opposite directions at either speed without reversing said motor.

26. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and motor driven

mechanism for driving said members simultaneously or separately in a direction to draw in their respective flexible feeding means at either a relatively high speed or a relatively low speed or to permit said members to rotate in a direction to pay out their respective flexible feeding means under various degrees of frictional resistance and including means for effecting rotation of said members in opposite directions at either speed without reversing said motor.

27. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and motor driven mechanism for driving said members simultaneously or separately in a direction to draw in their respective flexible feeding means at either a relatively high speed or a relatively low speed or to permit said members to rotate in a direction to pay out their respective flexible feeding means under various degrees of frictional resistance or without such resistance and including means for effecting rotation of said members in opposite directions at either speed without reversing said motor.

28. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating member each adapted to cooperate directly with flexible feeding means, and mechanism driven by said motor for driving said members in a direction to draw in their respective flexible feeding means including power transmission connections for driving said members including a plurality of friction clutches selectively operable to reverse the direction of rotation of said members, supplemental clutches for changing the rate of rotation of said members located in said power transmission connections at the opposite side of said first mentioned clutches from the motor, and controlling mechanism including mechanism for selectively actuating said different clutches.

29. In a mining machine, a machine frame slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and driving connections between said motor and said

- feed operating members operative to effect operation of said members by said motor at a plurality of speeds and in opposite directions at each of said speeds having speed 70
15 change gearing including a plurality of clutches and also having a plurality of selectively operable friction clutches between said first mentioned clutches and said motor.
30. In a mining machine, a machine frame 75
10 slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and driving connections between the motor and said feed operating members operative to effect operation 80
15 of said members by said motor at a plurality of speeds and in opposite directions at each of said speeds including speed changing gearing including a plurality of friction clutches operative when engaged to 85
20 change the speed of rotation of said feed operating members, and a plurality of selectively operable friction clutches between said first mentioned clutches and said motor.
31. In a mining machine, a machine frame 90
25 slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and driving connections between said motor and said members operative to effect operation of said members 95
35 by said motor at a plurality of speeds and in opposite directions at each of said speeds including speed changing gearing including a plurality of clutches between the motor and said feed operating members, and a plurality 100
40 of friction clutches selectively operable to reverse the direction of rotation of said feed operating members and arranged between said first mentioned clutches and said motor.
32. In a mining machine, a machine frame 105
45 slidable on its bottom on the mine floor, kerf cutting mechanism carried by said frame including an elongated kerf cutter projecting from said frame, a motor, and feeding means for the machine driven by said motor including relatively rotatable feed operating members each adapted to cooperate directly with flexible feeding means, and driving connections between the motor and said feed operating members operative to effect operation of said members by said motor at a plurality of speeds and in opposite directions 110
55 at each of said speeds having speed change gearing including a plurality of clutches and also having a plurality of selectively operable friction clutches between said first mentioned clutches and said motor.
- 60 33. A mining machine slidable on a mine bottom comprising a frame, cutting mechanism thereon including a projecting cutter bar disposed longitudinally of said frame and rigidly connected thereto throughout the cutting operation, and a circulating cutter chain on said bar, flexible feeding means and guiding means for said feeding means about which said flexible feeding means may be directed to enable lateral cutting in a face in either direction providing advance and receding portions during lateral cutting in one direction extending laterally in opposite direction from the opposite ends of said frame and having provision whereby said portions may be reversely disposed respectively as receding and advancing portions during lateral cutting in the opposite direction, a motor operatively connected with said cutter chain, and driving connections between said motor and said flexible feeding means including 115
65 relatively rotatable feed operating members operatively engaging the latter, and driving connections between the motor and said feed operating members operative to effect operation of said members by said motor at a plurality of speeds and in opposite directions 120
70 at each of said speeds having speed change gearing including a plurality of clutches and also having a plurality of selectively operable friction clutches between said first mentioned clutches and said motor.
- 75 34. A mining machine slidable on a mine bottom comprising a frame, cutting mechanism thereon including a projecting cutter bar disposed longitudinally of said frame and rigidly connected thereto throughout the cutting operation, and a circulating cutter chain on said bar, flexible feeding means and guiding means for said feeding means about which said flexible feeding means may be directed to enable lateral cutting in a face in either direction providing advance and receding portions during lateral cutting in one direction extending laterally in opposite direction from the opposite ends of said frame and having provision whereby said portions may be reversely disposed respectively as receding and advancing portions during lateral cutting in the opposite direction, a motor operatively connected with said cutter chain, and driving connections between said motor and said flexible feeding means including 125
80 relatively rotatable feed operating members operatively engaging the latter, and driving connections between the motor and said feed operating members operative to effect operation of said members by said motor at a plurality of speeds and in opposite directions 130
85 at each of said speeds having speed change gearing including a plurality of clutches and also having a plurality of selectively operable friction clutches between said first mentioned clutches and said motor.
- 90 35. A mining machine slidable on a mine bottom comprising a frame, cutting mechanism thereon including a projecting cutter bar disposed longitudinally of said frame and rigidly connected thereto throughout the cutting operation, and a circulating cutter chain on said bar, flexible feeding means and guiding means for said feeding means about which said flexible feeding means may be directed to enable lateral cutting in a face in either direction providing advance and receding portions during lateral cutting in one direction extending laterally in opposite direction from the opposite ends of said frame and having provision whereby said portions may be reversely disposed respectively as receding and advancing portions during lateral cutting in the opposite direction, a motor operatively connected with said cutter chain, and driving connections between said motor and said flexible feeding means including 135
95 relatively rotatable feed operating members operatively engaging the latter, and driving connections between the motor and said feed operating members operative to effect operation of said members by said motor at a plurality of speeds and in opposite directions 140
100 at each of said speeds having speed change gearing including a plurality of clutches and also having a plurality of selectively operable friction clutches between said first mentioned clutches and said motor.

- ting operations, and a circulating cutter chain on said bar, flexible feeding means and guiding means for said feeding means about which said flexible feeding means may be directed to enable a lateral cut in a face in either direction providing advance and receding portions during lateral cutting in one direction extending laterally in opposite directions from the opposite ends of said frame and having provision whereby said portions may be reversely disposed respectively as receding and advancing portions during lateral cutting in the opposite direction, a motor operatively connected with said cutter chain, and driving connections between said motor and said flexible feeding means including relatively rotatable feed operating members operatively engaging the flexible feeding means, and driving connections between the motor and said feed operating members operative to effect operation of said members by said motor at a plurality of speeds and in opposite directions at each of said speeds including speed changing gearing including a plurality of clutches operative when engaged to change the speed of rotation of the feed operating members and a plurality of selectively operable friction clutches between said first mentioned clutches and said motor.

30 36. A mining machine slidable on a mine bottom comprising a frame, cutting mechanism thereon including a projecting cutter bar disposed longitudinally of said frame and rigidly connected thereto throughout the cutting operation, and a circulating cutter chain on said bar, flexible feeding means and guiding means for said feeding means about which said flexible feeding means may be directed, in order to enable a lateral cut in a face in either direction, to provide advance and receding portions during lateral cutting in one direction extending laterally in opposite directions from the opposite ends of said frame and having provisions whereby said portions may be reversely disposed respectively as receding and advancing portions during lateral cutting in the opposite direction, a motor operatively connected with said cutter chain, and driving connections between the motor and said feed operating members operative to effect operation of said members by said motor at a plurality of speeds and in opposite directions at each of said speeds including speed changing gearing including a plurality of friction clutches operative when engaged to change the speed of rotation of the feed operating members and a plurality of friction clutches selectively operable to reverse the direction of feed and arranged between said first mentioned clutches and said motor.

35 38. In a mining machine, a machine frame slidable on its bottom on the mine floor, a motor carried by said frame, kerf cutting mechanism driven by said motor including a cutter chain carrying cutter bar projecting from said frame, and a driving element for said cutter chain, and feeding means for the machine driven by said motor including relatively rotatable feed operating members each adapted to cooperate directly with flexible feeding means, and driving connections between said motor and said members including a gear coaxial with said cutter chain driving element, gears meshing directly with said gear, worms driven by said last mentioned gears respectively, and worm wheels meshing with said worms and driven thereby at relatively different predetermined speeds.

40 39. In a mining machine, a machine frame slidable on its bottom on the mine floor, a motor carried by said frame, kerf cutting mechanism driven by said motor including a cutter chain carrying cutter bar projecting from said frame, and a driving element for said cutter chain, and feeding means for the machine driven by said motor including relatively rotatable feed operating members each adapted to cooperate directly with flexible feeding means, and driving connections between said motor and said members includ-

ing a gear coaxial with said cutter chain driving element, gears meshing directly with said gear, worms driven by said last mentioned gears respectively and rotating about parallel vertical axes, and worm wheels meshing with said worms and driven thereby at relatively different predetermined speeds.

40. In a mining machine, a machine frame 10 slidable on its bottom on the mine floor, a motor carried by said frame, kerf cutting mechanism driven by said motor including a cutter chain carrying cutter bar projecting from said frame, and a driving element for said cutter chain, and feeding means for the machine driven by said motor including relatively rotatable feed operating members each adapted to cooperate directly with flexible feeding means, and driving connections between said motor and said members including a gear coaxial with said cutter chain driving element, gears meshing with said gear, worms driven by said last mentioned gears respectively, worm wheels meshing with said worms, a transverse shaft coaxial with said 20 worm wheels and driven thereby at relatively different predetermined speeds, and driving connections between each of said members and said shaft.

41. In a mining machine, a machine frame 30 slidable on its bottom on the mine floor, a motor carried by said frame, kerf cutting mechanism driven by said motor including a cutter chain carrying cutter bar projecting from said frame, and a driving element for said cutter chain, and feeding means for the machine driven by said motor including relatively rotatable feed operating members each adapted to cooperate directly with flexible feeding means, and driving connections between said motor and said members including a gear coaxial with said cutter chain driving element, gears meshing with said gear, worms driven by said last mentioned gears respectively, worm wheels meshing with said 40 worms, a transverse shaft coaxial with said worm wheels and driven thereby at relatively different predetermined speeds, and clutches for selectively connecting said worm wheels to said shaft.

42. In a mining machine, a machine frame 50 slidable on its bottom on the mine floor, a motor carried by said frame, and feeding means for the machine driven by said motor including relatively rotatable feed operating members each adapted to cooperate directly with flexible feeding means, and driving connections between said motor and said members including a spur pinion rotatable about a vertical axis, spur gears meshing directly with said spur pinion, worms driven by said 60 spur gears respectively, and worm wheels meshing with said worms and driven thereby at relatively different predetermined speeds.

43. In a mining machine, a machine frame 70 slidable on its bottom on the mine floor, a motor carried by said frame, and feeding

means for the machine driven by said motor including relatively rotatable feed operating members each adapted to cooperate directly with flexible feeding means, and driving connections between said motor and said members including a spur pinion rotatable about a vertical axis, spur gears meshing directly with said spur pinion, worms driven by said spur gears respectively and rotating about parallel vertical axes, and worm wheels meshing with said worms and driven thereby at relatively different predetermined speeds. 75

44. In a mining machine, a machine frame 80 slidable on its bottom on the mine floor, a motor carried by said frame, and feeding means for the machine driven by said motor including relatively rotatable feed operating members each adapted to cooperate directly with flexible feeding means, and driving connections between said motor and said members including a spur pinion rotatable about a vertical axis, spur gears meshing with said spur pinion, worms driven by said spur gears respectively, worm wheels meshing with said worms, a transverse shaft coaxial with said 90 worm wheels and driven thereby at relatively different predetermined speeds, and driving connections between said shaft and said feed operating members.

45. In a mining machine, a machine frame 95 slidable on its bottom on the mine floor, a motor carried by said frame, and feeding means for the machine driven by said motor including relatively rotatable feed operating members each adapted to cooperate directly with flexible feeding means, and driving connections between said motor and said members including a spur pinion rotatable about a vertical axis, spur gears meshing with said spur pinion, worms driven by said spur gears respectively and rotating about parallel vertical axes, worm wheels meshing with said worms, a transverse shaft coaxial with said 105 worm wheels and driven thereby at relatively different predetermined speeds, and driving connections between said shaft and said feed operating members.

46. In a mining machine, a machine frame 110 slidable on its bottom on the mine floor, a motor carried by said frame, and feeding means for the machine driven by said motor including relatively rotatable feed operating members each adapted to cooperate directly with flexible feeding means, and driving connections between said motor and said members including a spur pinion rotatable about a vertical axis, spur gears meshing with said spur pinion, worms driven by said spur gears respectively, worm wheels meshing with said worms, a transverse shaft coaxial with said 120 worm wheels, and clutches for selectively connecting said worm wheels to said shaft.

47. In a mining machine, a machine frame 125 slidable on its bottom on the mine floor, a motor carried by said frame, and feeding

- means for the machine driven by said motor including relatively rotatable feed operating members each adapted to cooperate directly with flexible feeding means, and driving connections between said motor and said members including a spur pinion rotatable about a vertical axis, spur gears meshing with said spur pinion, worms driven by spur gears respectively and rotating about parallel vertical axes, worm wheels meshing with said worms, a transverse shaft coaxial with said worm wheels, and clutches for selectively connecting said worm wheels to said shaft. 75
48. In a mining machine feeding mechanism, relatively rotatable feeding members each adapted to cooperate directly with flexible feeding means, and motor operated driving means for said members including a motor driven element, a fast and slow predetermined speed change speed mechanism, and a reversing device in the drive between said motor driven element and said change speed mechanism whereby said members may be rotated in either of opposite directions and at different speeds while said motor driven element rotates continuously in a single direction. 80
49. In a mining machine, a motor, kerf cutting mechanism driven by said motor including a cutter chain carrying cutter bar and a driving sprocket for said cutter chain, a driving element coaxial with the rotatable with said sprocket, and feeding means for the machine including relatively rotatable feeding members each adapted to cooperate directly with flexible feeding means, and driving connections between said driving element and said members including a selective change speed device for effecting drive of said members at different predetermined speeds including separate relatively high and low speed gear trains branching from said driving element and selectively operable to effect drive of said members. 85
50. In a mining machine, a motor, kerf cutting mechanism driven by said motor including a cutter chain carrying cutter bar and a driving sprocket for said cutter chain, a driving element coaxial with and rotatable with said sprocket, and feeding means for the machine including relatively rotatable feeding members each adapted to cooperate directly with flexible feeding means, and driving connections between said driving element and said members including a reversing device whereby said members may be driven in either of opposite directions while said driving element rotates continuously in a single direction. 90
51. In a mining machine, a motor, kerf cutting mechanism driven by said motor including a cutter chain carrying cutter bar and a driving element for said cutter chain, and feeding means for the machine including relatively rotatable feeding members each 95
- adapted to cooperate directly with flexible feeding means, and driving connections between said cutter chain driving element and said members including a change speed device for effecting drive at a plurality of speeds and a reversing device whereby said members may be driven in either of opposite directions at either speed while said cutter chain driving element rotates continuously in a single direction. 100
52. In a mining machine, a motor, kerf cutting mechanism driven by said motor including a kerf cutter, and feeding means for the machine including relatively rotatable feeding members each adapted to cooperate directly with flexible feeding means, and driving connections between said motor and said feeding members for driving the latter in either of opposite directions at similar speeds while said kerf cutter is driven and the motor operates both continuously in the same direction. 105
53. In a mining machine, a motor, kerf cutting mechanism driven by said motor including a kerf cutter, and feeding means for the machine including relatively rotatable feeding members each adapted to cooperate directly with flexible feeding means, and plural speed driving connections between said motor and said feeding members for driving the latter in either of opposite directions at either speed while said kerf cutter is driven and the motor operates both continuously in the same direction. 110
54. In a mining machine, a motor, cutting mechanism driven thereby including an elongated kerf cutter, and feeding means driven by said motor including relatively rotatable feed operating and controlling members rotating on horizontal axes and each adapted to cooperate with flexible feeding means and plural speed mechanism for independently driving said members at either a relatively low speed or a relatively high speed and selectively in opposite directions at either speed while said motor runs continuously in one direction. 115
55. In a mining machine, a motor, cutting mechanism driven thereby including an elongated kerf cutter, and feeding means driven by said motor including relatively rotatable feed operating and controlling members rotating on horizontal axes extending transversely of the machine and each adapted to cooperate with flexible feeding means and plural speed mechanism for independently driving said members at either a relatively low speed or a relatively high speed and selectively in opposite directions at either speed while said motor runs continuously in one direction. 120
56. In a mining machine, a motor, cutting mechanism driven thereby including an elongated kerf cutter, and feeding means driven by said motor including coaxially arranged 125
- 130

5 relatively rotatable feed operating and controlling members each adapted to cooperate with flexible feeding means and plural speed mechanism for independently driving said members at either a relatively low speed or a relatively high speed and selectively in opposite directions at either speed while said motor runs continuously in one direction.

10 57. In a mining machine, a motor, cutting mechanism driven thereby including an elongated kerf cutter, and feeding means driven by said motor including coaxially arranged relatively rotatable feed operating and controlling members rotating on horizontal axes and each adapted to cooperate with flexible feeding means, and plural speed mechanism for independently driving said members at either a relatively low speed or a relatively high speed and selectively in opposite directions at either speed while said motor runs continuously in one direction.

15 58. In a mining machine feeding mechanism, a motor, relatively rotatable feed members each adapted to cooperate directly with flexible feeding means, and driving connections between said motor and said members for rotating said members either separately or simultaneously at relatively high speed or at relatively low speed and at the same angular rates and including reversing means for effecting rotation of said members in either of opposite directions at either speed without reversing said motor.

20 59. In a mining machine feeding mechanism, a motor, relatively rotatable feeding members arranged at and driven from the same end of said motor and each adapted to cooperate directly with flexible feeding means, and plural speed driving connections between said motor and said members for rotating said members in a direction to draw in their respective flexible feeding means at different speeds and including reversing means for effecting rotation of one of said members in either of opposite directions at the same angular speeds in either direction without reversing said motor.

25 60. In a mining machine feeding mechanism, a motor, relatively rotatable feeding members each adapted to cooperate directly with flexible feeding means, and plural speed driving connections between said motor and said members for rotating said members in a direction to draw in their respective flexible feeding means at different speeds and including reversing means for effecting rotation of said members in either of opposite directions at the same angular speeds in either direction without reversing said motor.

30 61. In a mining machine feeding mechanism, a motor, relatively rotatable feeding members each adapted to cooperate directly with flexible feeding means, and driving connections between said motor and said members for driving said members at a relatively

high predetermined speed or at a relatively low predetermined speed and including reversing mechanism for effecting rotation of one of said members in either of opposite directions at either speed without reversing said motor. 70

62. In a mining machine feeding mechanism, a motor, relatively rotatable feeding members each adapted to cooperate directly with flexible feeding means, and driving connections between said motor and said members for driving said members at a relatively high predetermined speed or at a relatively low predetermined speed and including reversing mechanism for effecting rotation of either member in either of opposite directions at either speed without reversing said motor. 75

63. In a mining machine feeding mechanism, a motor, relatively rotatable feeding members each adapted to cooperate directly with flexible feeding means, and driving connections between said members for rotating said members separately or simultaneously at relatively high speed or at relatively low speed and including reversing means for effecting rotation of said members in either of opposite directions at either speed without reversing said motor. 80

CERTIFICATE OF CORRECTION.

Patent No. 1,875,334.

September 6, 1932.

MORRIS P. HOLMES.

It is hereby certified that error appears in the printed specification of the above numbered patent requiring correction as follows: Page 2, line 63, for "slidably" read suitably; and page 11, line 32, claim 49, for "the" read and; and that the said Letters Patent should be read with these corrections therein that the same may conform to the record of the case in the Patent Office.

Signed and sealed this 30th day of October, A. D. 1934.

Leslie Frazer

Acting Commissioner of Patents.
